UNITED STATES PATENT OFFICE.

GEORGE BECKER, OF MANSFIELD, OHIO.

WAGON END-GATE.

SPECIFICATION forming part of Letters Patent No. 295,099, dated March 11, 1884.

Application filed April 12, 1883. Renewed February 13, 1884. (Model.)

To all whom it may concern.

Be it known that I, GEORGE BECKER, of Mansfield, in the county of Richland and State of Ohio, have invented a new and useful Improvement in Wagon End-Gates, of which the following is a specification, reference being had to the accompanying drawings.

The invention relates to an improvement in wagon end-gates; and it consists in an end-gate having hinges secured to the side of the wagon-bed and to the end-gate, the opposite end having a catch or fastener attached to the end-gate, and so constructed that it will pass on the outside of the wagon-bed, where it is held firmly by a bolt or pin.

Referring to the accompanying drawings, Figure 1 is a front view of an end-gate and wagon-bed embodying the elements of my invention. Fig. 2 is a top view of same.

20 A indicates the end-gate, which is constructed by securing battens D to it, to prevent warping and splitting of the end-gate.

B are the hinges, the portion B being secured to the batten D, the portion C being bolted to the inside of the side of the wagon-bed L. The portion of the hinge marked C is constructed of a plate having two projecting lugs, the lower lug having a hole to admit of the pin on part B. The upper lug is made with a 30 curved slot intersecting with the hole. The curve-slot is for purpose of allowing the end-gate to be taken off at pleasure.

The novel feature in the end-gate is in the construction of the hinge and catch, and in the manner they are attached to and operate the end-gate.

E represents the lock or catch for the purpose of holding the end-gate in position, which is composed of a Z-shaped plate, W, and 40 hinged plate N, the plates N and W being

hinged at the angle a. The plate W is attached to the end-gate A by bolts or screws. To the side P of the wagon-box is secured the plate J. This plate has a lug or projection, b, projecting from its face. This lug passes 45 through the hinged plate N, and is for the purpose of holding the end-gate in position when the bolt G is removed. The bolt G is for the purpose of clamping the hinged catch firmly together when the end-gate is placed in its 50 proper position.

When the operator wishes to remove the end-gate, the screw or bolt G is first removed. The plate N will then be easily removed from the lug or catch b, allowing the end-gate A to 55 swing upon the hinges B when the end-gate swings to a parallel line with the side L. The end-gate can be removed from the wagon-bed simply by raising the end-gate vertically, the plate B passing through the curved slot s in 60 the lug c.

What I claim as my invention, and desire to secure by Letters Patent, is—

The combination of the end-gate A, hinged to the wagon-body by the hinges B C, the part 65 C being formed with the curved slot s, whereby the end-gate may readily be disconnected from the body, with the catch E, formed of the plates W and N, adapted to hold the gate closed by means of the bolt G, and plate J, 70 provided with the knob b, as specified.

In testimony that I claim the foregoing improvement in wagon end-gates, as above described, I have hereunto set my hand this 9th day of April, 1883.

GEORGE BECKER.
